Primary Examiner — David Muller(74) *Attorney, Agent, or Firm* — Pate Baird, PLLC(57) **CLAIM**

The ornamental design for a suction probe, as shown and described.

DESCRIPTION

FIG. 1 is an isometric view thereof;

FIG. 2 is a top plan view thereof;

FIG. 3 is a bottom plan view thereof;

FIG. 4 is a right side elevation view thereof;

FIG. 5 is a left side elevation view thereof;

FIG. 6 is a rear elevation view thereof;

FIG. 7 is a front elevation view thereof;

FIG. 8 is a cross-sectional rear elevational view thereof, taken along line 8-8 in FIG. 2; and,

FIG. 9 is a cross-sectional right side elevational view thereof, taken along line 9-9 in FIG. 2.

The broken line showing of parts of the drawings is included for the purpose of illustrating use and environment and forms no part of the claimed design.
